PLUG-IN ELECTRICAL RECEPTACLE

Walter P. Keller, Chicago, Ill.

Application June 28, 1949, Serial No. 101,838

4 Claims. (Cl. 339—191)

1

This invention relates to plug-in connectors; in particular, it concerns a greatly improved receptacle adapted for co-operation with prong-type plugs. While the primary field of usefulness of such devices is as connectors in electrical circuits, their range of usefulness is not limited to such applications.

An object of the present invention is to provide a receptacle or socket for prong-type plugs which combines ease of manufacture with exceptional mechanical strength and stability.

Another object of the present invention is to provide a receptacle of the type described which is susceptible of extreme economy in manufacture, being formed, in a typical embodiment, of two molded pieces of insulating material and two readily formed metal parts.

Still another object of the present invention is to provide a receptacle of the type described wherein complete freedom from relative movement of parts is assured without the necessity for any permanent connection, by riveting or otherwise, between the metal contact members and the structural parts normally formed of insulating material.

A still further object of the present invention is to provide a receptacle of the type described wherein novel and simple, yet extraordinarily effective, means are provided for locking the metal contact members in their proper position within the structural members and for insuring against dislocation of such members as a result of forces transmitted by the prongs of the plugs with which the receptacle is used.

A conspicuous disadvantage of prior-art receptacles of the type under consideration is that such receptacles required rivets for effective locking of the metal contact members into the structural parts of the receptacle. This construction either made the receptacle dangerous by providing a pair of electrically "hot" rivets in an accessible place on the back of the socket or it required that the rivets be set in a counter-sunk recess and protected from external access by sealing wax or other material. Either alternative was highly objectionable—the first because it was dangerous, and the second because it was time-consuming and expensive. Accordingly, one of the principal objects of this invention is to provide a receptacle wherein positive mechanical locking of the contact members against movement is accomplished without any exposure, on the external parts of the receptacle, of electrically "hot" conductors.

Other objects and advantages of my invention will appear as the specification proceeds.

2

I have, in the accompanying drawing, illustrated two embodiments of my invention. Of the various figures of the drawing, Fig. 1 is a perspective view of one illustrative embodiment of my invention, shown in conjunction with a plug-in fuse holder; Fig. 2 is a plan view of the embodiment of Fig. 1 showing the manner in which it may be mounted on the forward wall of a terminal box; Fig. 3 is a side sectional view of the receptacle of Fig. 1; Fig. 4 is an exploded sectional view similar to Fig. 3 with the parts separated to bring out clearly their coaction; Fig. 5 is a plan view of the base portion of the embodiment of Fig. 1, shown with the contact members in position but with the cover member removed; Fig. 6 is a bottom view of the cover member of the embodiment of Fig. 1, as seen looking upward from the under side when the cover member is removed from the base member; Fig. 7 is a plan view of a second embodiment of my invention; Fig. 8 is a plan view of the embodiment of Fig. 7 as it appears with the cover member removed but with the contact members in place; Fig. 9 is a sectional view of the embodiment of Fig. 7, the section being taken along the lines 9—9 of Fig. 7; and Fig. 10 is an exploded sectional view similar to Fig. 9 but with the parts separated to bring out the manner in which they coact.

The first embodiment of my invention, as shown in Figs. 1-6, comprises a base member 10, a cover member 11, and a pair of metal contact members 12 and 13 respectively.

The embodiment of my invention shown in Figs. 1-6 is adapted for back-of-panel mounting in a terminal box 14. As shown in Fig. 2, the panel or forward wall of the terminal box in question is provided, by stamping or otherwise, with an aperture adapted to receive the forward face of my receptacle. Since the embodiment shown is provided with a circular forward face, the aperture should be circular and equipped with a pair of inwardly extending ears, typified by ear 14a in Fig. 2, for facilitating rigid mounting of my receptacle. The base member 10 and the cover member 11 are formed for effecting a co-operative fit with one another, and are held together by a pair of screws 16 which pass through suitable apertures 17 in cover member 11 and screw into threaded apertures 18 in base member 10. When the receptacle is to be mounted in a terminal box, the screws 16 may be passed through apertured ears 14a before entering cover member 11, and the assembly of my receptacle and its firm support on a terminal box may thus be accomplished in a single operation. To facilitate mounting of my receptacle and to assure

complete freedom from movement in response to torsional stresses, a pair of recesses 19, shaped to fit tightly with ears 14a, are provided in the forward face of cover member 11.

Base member 10 and cover member 11 of my receptacle will normally be formed entirely of insulating material and, in the normal, economical mode of manufacture, will be respectively molded from thermosetting plastic.

The forward face of cover member 11 is provided with a pair of slots 20 and 21, intended to receive the contact prongs 22 of the fuse holder 23 or other plug-in device being used with the receptacle. In the embodiment shown, slot 20 is somewhat shorter than slot 21 so as to permit use with a polarized plug to insure against inadvertent reversal of electrical connections through the receptacle. If the receptacle is intended for use in applications wherein polarity is of no significance, slots 20 and 21 may be made equal in length.

As may be seen best from Figs. 3 and 4, base member 10 is provided with a pair of symmetrically disposed recesses 24 and 25, formed as seats for metallic contact members 12 and 13. In the embodiment shown, contact members 12 and 13 include spring brush or rubbing members, denoted respectively 26 and 27, riveted, by rivets 28 and 29 respectively, to extension members 30 and 31. Extension members 30 and 31 consist of relatively heavy and rigid metal bars which underlie the spring members 26 and 27. The portion of members 30 and 31 which are secured by the rivets to the bottom portion of the spring members are flat on both their upper and lower faces and are substantially coextensive with the bottom portion of the spring members along two sides thereof. Members 30 and 31 respectively extend beyond the spring members on two sides, however, forming respectively side extensions 30a and 31a and terminal-carrying extensions 30b and 31b.

To permit the under side of members 30 and 31 to seat firmly on the bottoms of recesses 24 and 25, sub-recesses 24a and 25a may be provided to receive the rivets 28 and 29 respectively.

Terminal extensions 30b and 31b may be provided with apertures 32 to receive terminal screws 33. Electrical contact may be made to contact members 12 and 13 in the conventional manner by bending wires around screws 33 and securing them by tightly screwing screws 33 into apertures 32.

As may be seen by reference to Figs. 1, 3, and 4, the terminal extensions 30b and 31b emerge from base member 10 and project externally of the receptacle. Recesses 34 and 35 are provided in the outer rim of base member 10 to permit terminal extensions 30b and 31b respectively to emerge from base member 10 in a position such that the upper surfaces of terminal extensions 30b and 31b are flush with the rim of base member 10 when contact members 12 and 13 are properly seated in recesses 24 and 25 respectively.

The cap or cover member 11 is formed generally for co-operation with base member 10, and its outer conformation should normally match that of base member 10. In the present example, both base member 10 and cover member 11 are formed in a generally cylindrical shape with a circular cross section. The height, or axial length, of cover member 11 is chosen to provide a limited amount of clearance between the top of cover member 11 and the uppermost extension of contact members 12 and 13 when those members are properly seated in the base member. As may be

seen from Figs. 1, 3, and 4, the lower rim of cover member 11 is formed to co-operate with and fit snugly to the rim of base member 10.

Along its midline midway between slots 20 and 21, cover member 11 is provided with a ridge or brace member 36 which extends as a solid body from the top of cover member 11 to the plane of the outer rim thereof. Member 36 extends beyond the plane just mentioned, but in its extension it is bifurcated to form a pair of projecting feet 37 and 38. In the embodiment shown, feet 37 and 38 are parallel to one another and are separated by a distance substantially equal to the thickness of the wall separating recess 24 from recess 25. The length of foot members 37 and 38 is equal to the axial distance between the rim of base member 10 and the upper surface of members 30 and 31 when they are seated in recesses 24 and 25 respectively.

In the assembly of the embodiment of my invention shown in Figs. 1-6, the contact members 12 and 13 are first seated in recesses 24 and 25. This results in the under portions of members 30 and 31 resting securely on the bottoms of recesses 24 and 25 respectively, the over-all length of such bottom portions being substantially equal to the length of recesses 24 and 25. When such seating has been accomplished, terminal extensions 30b and 31b are seated in recesses 34 and 35 with their upper surfaces flush with the rim of base member 10. Similarly, side extensions 30a and 31a occupy the innermost portions of recesses 24 and 25 respectively. The cover member 11 is then placed over base member 10 and pressed into firm engagement therewith. This causes feet 37 and 38 to engage and press upon side extensions 30a and 31a respectively, and at the same time the outer rim of cover member 11 is in engagement with and pressing upon the upper surfaces of terminal extensions 30b and 31b. Screws 16 may then be inserted and screwed into threaded apertures 18 to complete the assembly of my receptacle. It is to be noted that the novel construction of my receptacle provides absolute anchorage of contact members 12 and 13 against movement, regardless of the magnitude or direction of forces which may be applied to the spring members 26 and 27 by the prongs 22 of a plug being inserted in the receptacle. Similarly, no matter how tightly prong members 22 may be held by spring members 26 and 27, the forcible removal of the prongs 22 cannot cause any shift in the position of contact members 12 and 13.

In Figs. 7-10 inclusive, I have shown a second embodiment of my invention which, while it embodies the same basic novel conception as the first embodiment, is adapted to somewhat different applications. The receptacle shown in Figs. 1-6 is of a type likely to be employed in relatively high-power electrical installations in factories and other industrial buildings. The wiring in nearly all such structures is carried in conduits and terminated in terminal boxes. Hence the construction of the Fig. 1 embodiment, with its externally projecting terminal extensions 30b and 31b, is appropriate to the applications for which that receptacle is designed. In many wiring installations, however, conduits and terminal boxes are not employed and it is accordingly desirable that no externally accessible portion of the receptacle be electrically "hot." This is particularly true in post-construction wiring in homes, garages, and other domestic buildings. In such buildings electrical extensions are very frequent-

ly installed by running open wiring along the baseboards or mouldings; frequently a receptacle is inserted and the line continued beyond that receptacle to one or more other receptacles. I have provided, and have shown in Figs. 7-10, a receptacle for such applications which is entirely safe for use, even in situations where children and other persons inexperienced with electricity have access to the wiring.

As with the other form of my invention just described, the receptacle of Figs. 7-10 comprises a base member, denoted 50, a cover member, denoted 51, and a pair of contact members, denoted generally 52 and 53 respectively.

As with the other embodiment of my invention shown and described, the cover member 51 is provided with a pair of slots 54 to afford a means of access of the prongs of a plug to the contact members 52 and 53. Since polarized connection is normally not necessary in applications of the sort for which the Fig. 7 embodiment is designed, the slots 54 are shown as being of the same width. It will of course be understood that, just as with the Fig. 1 embodiment, the slots may be polarized or not as preferred.

The cover member 51 is suitably apertured to receive screws 55 which serve to lock together the cover and base members 51 and 50 respectively. Screws 55 pass through apertures 56 in base member 50. If desired, screws 55 may be machine screws, in which case the apertures 56 may be suitably threaded to receive them. This type of construction is desirable for extension cords and other applications wherein firm anchorage of the receptacle to a wall is not called for. If the receptacle is to be anchored to a wooden moulding, baseboard, or floor, screws 55 may be of the tapered wood-screw variety and apertures 56 may be made large enough to clear their shanks. In such a case, the screws 55 can perform the double function of anchoring the respective structural parts of the receptacle together and at the same time anchoring the same to the baseboard or other fixed object.

The contact members 52 and 53 comprise respectively spring members 57 and 58 and base members 59 and 60, anchored together respectively by rivets 61.

The base members 59 and 60 are somewhat wider than spring members 57 and 58 so as to provide side extensions 59a and 60a alongside each of the spring members 57 and 58. Moreover, the base members 59 and 60 are extended in length a short distance beyond the ends of spring members 57 and 58 so as to provide connector terminal surfaces 59b and 60b. Each of the connector terminal surfaces 59b and 60b is provided with a threaded aperture to receive a terminal screw 62.

Base member 50 is provided with a pair of parallel recesses 63 and 64, said recesses being disposed symmetrically with respect to the mid-line of base member 50. The recesses 63 and 64 are shaped to receive contact members 52 and 53; sub-recesses 63a and 64a in the bottoms, respectively, of recesses 63 and 64 accommodate the downwardly projecting portions of rivets 61 and terminal screws 62. The width of recesses 63 and 64 is substantially equal to the width of base members 59 and 60 of contact members 52 and 53. A pair of small recesses 65 are provided in the upper rim of base member 50 to permit electric cords to pass into the receptacle for terminal connections to screws 62.

The cover member 51 of this embodiment of

my invention is hollow, like the cover member of the Fig. 1 embodiment. Its outer wall is cylindrical in shape, to register and co-operate with the cylindrical base member 50. The axial distance from the top of cover member 51 to the lower rim thereof is adjusted to provide a limited clearance between the top of member 51 and the uppermost portions of spring members 57 and 58.

A pair of downwardly extending feet 66 and 67 constitute an integral extension of the side wall of cover member 51; feet 66 and 67 are diametrically opposite one another and are of such width that they may be readily received within recesses 63 and 64 respectively. The distance between the rim of member 51 and the lowermost face of feet 66 and 67 is equal to the distance between the rim of base member 50 and the upper surface of members 59 and 60 when they are properly seated within recesses 63 and 64.

A midline ridge or brace member 68 extends downward along the midline of cover member 51 from the underside of the top thereof; it continues downwardly as a solid member to the point flush with the rim of member 51; therebelow the member 68 is bifurcated to form a pair of feet 69 and 70, separated one from another by a distance substantially equal to the thickness of the wall separating recess 63 from recess 64. The length of feet 69 and 70 is, in the embodiment shown, equal to that of feet 66 and 67.

In the assembly of the embodiment of my invention shown in Figs. 7-10, the contact members 52 and 53 are first securely seated in recesses 63 and 64. Wires may be connected to terminal screws 62 either before or after the seating of contact members 52 and 53, as desired. When the wires have been connected to terminals 62, they may be carried externally to the receptacle through one or both of the recesses 65. Since terminal screws 62 and contact surfaces 59b are provided on opposite sides of contact members 52 and 53, wiring may be carried "straight through" if desired, one cord coming in through one of the recesses 65 and the other cord departing through the other recess 65, as shown in Figs. 7 and 8.

After the contact members have been seated in the recesses 63 and 64, the cover member 51 is seated over base member 50. This results in a snug matching fit between the respective rims of members 50 and 51, while at the same time feet 66, 67, 69, and 70 come firmly into contact with and press upon the side extension surfaces 59a and 60a of the contact members 52 and 53. Thus the contact members are firmly anchored against movement when the cover member is in place, just as with the embodiment of my invention shown in Figs. 1-6. After the cover member 51 is in place, screws 55 may be inserted and the receptacle is thereupon ready for use. Completely dependable anchorage of the contact members 52 and 53 is thus accomplished, and no electrically "hot" conductors are manually accessible from the outside of the receptacle. Thus the novel construction of my receptacle sets new standards both of safety, mechanical strength, simplicity, and economy of manufacture.

While I have in this specification described in considerable detail two embodiments of my invention, this was for purposes of illustration only. It is to be understood that many changes in details may be made by those skilled in the art without departing from the spirit of my inven-

tion. It is accordingly my desire that the scope of my invention be not limited to the specific embodiments illustrated but that it be determined solely with reference to the appended claims.

I claim:

1. A receptacle for a prong-type plug comprising a base member provided with a recess, a spring contact member adapted to receive in spring engagement a prong of said plug, said contact member being formed for entry in said recess and being provided with a pair of side extensions situated respectively on opposite sides of said contact member, and a cover member comprising a slot positioned over the recess to admit the prong to engagement with the contact member and being provided also with a foot adapted to enter the recess alongside the contact member, said spring contact member being clamped against movement when the cover member and base member are fitted together by the pressure of the foot on one of said side extensions and by the pressure of the rim of the cover member on the other of said side extensions.

2. A receptacle according to claim 1 wherein the rim of the base member is provided with a recess for receiving said other side extension, said other side extension being locked in said last-mentioned recess and secured against movement by being clamped between the rim of the cover member and the bottom of said recess.

3. A receptacle for a prong-type plug comprising a first structural member provided with a pair of recesses, a spring contact member for each recess adapted to receive in spring engagement one of the prongs of said plug, each of said contact members being respectively formed for entry in said recesses and being provided with a pair of side extensions respectively situated on opposite sides of the contact member, and a second structural member formed to fit co-operatively on the first structural member, said second structural member being provided with feet adapted to enter the respective recesses and to press on one of the side extensions of each con- 45

tact member to lock the same in position between said feet and said first structural member, one of said structural members having also a pair of rim recesses for accommodation of the other pair of side extensions, said second side extensions being received in said recesses and locked against movement by being clamped between the two structural members.

4. A receptacle for a prong-type plug comprising a base member provided with a pair of recesses oriented side by side in bilaterally symmetrical position and separated one from another by a wall extending along the midline of said base member, a spring contact member for each recess adapted to receive in spring engagement one of the prongs of said plug, each of said contact members being respectively formed for entry in said recesses and being provided with a side extension in surface contact with the base member when said contact members are situated in said respective recesses, and a cover member formed for co-operative fit on the base member, said cover member comprising slots positioned over said recesses to admit said prongs to engagement with those respective contacts and being provided also with a midline ridge member bifurcated at its lower extremity to straddle said midline wall of the base member and to provide thereby a pair of feet adapted to enter the respective recesses and to press on said side extensions for clamping the same in position against movement when the cover member and the base member are fitted together.
